UNITED STATES PATENT OFFICE.

WILLIAM KINGSLAND, OF LONDON, ENGLAND.

RATCHET-OPERATED ELECTRIC SWITCH.

SPECIFICATION forming part of Letters Patent No. 743,173, dated November 3, 1903.

Application filed June 1, 1903. Serial No. 159,600. (No model.)

To all whom it may concern:

Be it known that I, WILLIAM KINGSLAND, a subject of the King of Great Britain, and a resident of London, England, have invented certain new and useful Improvements in or Connected with Ratchet-Operated Electric Switches, and of which the following is a specification.

This invention has reference to rotary electric switches to which uniform step-by-step motions are to be communicated for the purpose of alternately making or breaking an electric circuit, for inserting and cutting out resistances, or for other purposes.

In the specification of United States patent granted to myself, No. 713,992, dated November 18, 1902, I have described such a switch to which step-by-step rotary motions are communicated by an operating-spindle capable of being moved in either direction from a zero position through a limited distance. This spindle carried two oppositely-engaging pawls, one of which was caused to engage and to operate an intermittent ratchet-wheel carrying the movable part of the switch and to so turn the switch in the same direction in which the operating-spindle was moved from its zero position. When the operating-spindle was moved in the other direction from its zero position, the other pawl operated and moved the switch in the reverse direction—that is, in the same direction as the arm. In this construction the extent of the movements of the operating-spindle was limited by certain ratchet-clutch mechanism, which, however, had no connection whatever with the parts by which the switch directly received its motion, and it was necessary to hold one of the switch ratchet-pawls out of action while the other pawl was operating.

Now the present invention refers to improved mechanism for communicating to such rotary switches the required accurately-defined step-by-step motions, but always in one and the same direction, by means of the limited partial rotation in either direction of the operating-spindle from its normal or zero position.

According to the present invention, as well as according to my previous patent, No. 713,992, the spindle is rocked by means of an arm or wheel, which may be operated by hand

in either direction from a normal position of rest, and at each operation the switch is moved through one step of its motion. Such an operating-arm therefore is very suitable for being operated by a tappet action, and the switch is eminently applicable for use in electric traction.

According to the present invention the means—that is, the ratchet-clutch mechanism—which was only employed for the purpose of limiting the motion of the arm and for returning it to position, in my Patent No. 713,992, is now so altered in construction and action that it not only serves those offices which it originally carried out, but it also serves the office of actuating a rotary pawl-carrying ring through a definite angle in a forward direction in order to rotate the moving part of the switch through its definite angle, and when the said mechanism is returned by spring action to bring back the arm to its zero position it carries back with it inoperatively the aforesaid pawl-carrying ring to position for the next operation, and consequently the rotary part of the switch receives a step-by-step motion in one and the same direction, no matter in what direction the operating-arm is moved.

An example of construction of ratchet-operated electric switch according to this invention will now be described with reference to the accompanying drawings.

Figure 1 is a vertical longitudinal section of the apparatus with its operative and controlling mechanism inclosed in a case, the design being such as to render the device applicable for use in electric traction. Fig. 2 is an end elevation showing the casing and the arm by which the aforesaid spindle receives its motion. Fig. 3 is a left-hand transverse sectional elevation on the line X Y of Fig. 1. Fig. 4 is a right-hand transverse sectional elevation, also on the line X Y of Fig. 1. The part of the mechanism by which the angular motions of the spindle are limited in both directions, by which the spindle is returned to its normal position, and by which a pawl-carrying ring is operated, as hereinafter described, is illustrated detached from its carrying parts at Figs. 5, 6, 7, and 8, Fig. 5 illustrating by an elevation and two opposite end views a helically-toothed wheel

which follows the angular rotative motions of the spindle. Fig. 6 shows by similar views an intermediate toothed wheel having helical teeth on both its faces and adapted to engage 5 upon one face with the wheel shown at Fig. 5. Fig. 7 is a similar view of a motor-screw, hereinafter described, having helical ratchet-like teeth upon one face, which engage with the teeth upon one face of the wheel shown 10 at Fig. 6; and Fig. 8 shows in elevation the assemblage of the parts shown at Figs. 5, 6, and 7. Fig. 9 is an end elevation, and Fig. 10 a vertical transverse section showing a pawl-carrying 15 ring detached, which communicates a step-by-step motion to a ratchet-wheel connected to the moving part of the switch. Fig. 11 is an end elevation of the step-by-step ratchet-wheel detached, aforesaid; and Fig. 12 is a side elevation of the same part. A modified 20 construction of the pawl-ring is shown at Figs. 13 to 16, Fig. 13 being a cross-section, and Fig. 14 an elevation, of the carrying-ring, Fig. 15 an elevation of a ratchet pawl-ring, and Fig. 16 a cross-section of the carrying- 25 ring with the pawl-ring in position therewith.

The spindle 1 is carried in bearings and is capable of being given a partial rotation in either direction by an arm 2 or equivalent part, its automatic return to the normal position of rest, (illustrated at Fig. 2,) as well as its extent of motion, being advantageously effected and defined by devices hereinafter described. The arm 2 or a part equivalent thereto may be operated by hand or by a tappet 35 action.

The bearings of the spindle 1 are formed in or carried by a casing which entirely incloses the mechanism and is effective in excluding water and detritus. This casing in the construction shown is made in two parts 3, 4, which are bolted together. The part 3 is formed with a neck, into which is screwed a cup-shaped bearing 5 for the outer end of the spindle 1, while the opposite end of the spindle has a bearing in a cylindrical part, which projects on the inner face of the part 4 of the casing, and the end collar of the spindle is covered by a cap 6. The spindle thus carried in bearings in the casing (presumably, for the purpose of this description, in a horizontal position) carries near its outer end—that is, near the end upon which the arm 2 is mounted—a wheel 7, Figs. 1, 5, and 8, hereinafter termed the "spindle-wheel." This wheel 7 is formed 55 with a squared bore and fits onto a squared portion of the spindle 1, so that it turns with the spindle while it is supported against end thrust by ball-bearings 8, acting against a race carried by bearings 5. The spindle-wheel 60 7 is formed upon its inner face with ratchet-like teeth having helical faces—that is, the inclined faces of the teeth are made as portions of screw-threads.

The teeth of the wheel 7 engage similarly-formed teeth upon the adjacent face of an intermediate wheel 9, which latter is loosely mounted upon the aforesaid spindle 1. The

intermediate wheel 9, Figs. 1, 6, and 8, upon its opposite face is formed with another set of ratchet-like teeth sloping in a direction 70 opposite to the direction of the teeth upon the other face of the intermediate wheel, and these teeth engage similarly-formed teeth upon the end of a cylindrical part 10, Figs. 1, 7, and 8, which is loosely mounted upon the 75 same spindle 1.

It has been previously stated that the ratchet-like teeth are made as portions of screw-threads, and this being so the screw-threads are continued around the periphery 80 of the cylindrical part 10, cutting away the core for a short distance of that cylindrical part at the end adjacent to the intermediate wheel 9, so as to allow the male screw-threads to project beyond such end and to form the 85 face ratchet-like teeth, which engage the teeth of the intermediate wheel. There would thus be as many screw-threads cut upon the periphery of the cylindrical part 10 as there are ratchet-like teeth around the face of the intermediate wheel 9—that is, if there are three teeth on the intermediate wheel 9 the screw formed upon the exterior of the cylindrical part 10 would be a triple-threaded screw. There is then provided means by which the 90 cylindrical part 10 (hereinafter termed the "motor-screw") shall be prevented from rotating while being permitted to have a limited and definite amount of traverse motion in the direction of the axis of the spindle 1, and such 100 means consist of projections 11, extending from the periphery of the motor-screw 10, entering longitudinal slots 12 in the bearing-sleeve 5, which is screwed and held stationary in the casing 3. The projections 11 are 105 clearly shown at Fig. 7. There is then provided a spring 13, which may conveniently be arranged around the spindle 1, acting against a part of the casing and bearing up against the motor-screw 10 and tending to 110 maintain it in face contact with the intermediate wheel 9, and consequently to maintain the intermediate wheel in its turn in face contact with the spindle 7.

When the operating-arm 2 is rocked in one 115 direction, the teeth of the spindle-wheel 7 will slide against the teeth of the intermediate wheel 9. The teeth of the latter will interlock with the end of the motor-screw 10, traverse the latter along the spindle 1, compress the spring 13 until the projections 11 on the motor-screw come to the end of the groove 12 in the bearing-sleeve 5, by which its motion is limited, and then the angular motion of the arm 2 will be stopped. The arm 120 2 will be brought back again by the spring 13, returning the motor-screw 10 to its original position by causing the teeth of the intermediate wheel 9 to slide against the teeth of the spindle-wheel 7. If the operating-arm 125 2 is moved in the reverse direction, the spindle-wheel 7 will interlock with the intermediate wheel 9, and the rotation of the latter wheel will operate upon the end faces of the

male threads of the motor-screw 10 with a like result. It is to be observed that the motor-screw 10 never rotates, its limited movements being only in the direction of the axis 5 of the spindle.

The movable part 14 of the switch proper, which is shown in section at Fig. 1 and by dotted lines at Fig. 3 and to which is to be given the step-by-step rotary motion in one direction only, according to this invention is mounted upon a sleeve 15, (see also Fig. 12,) which may be exteriorly polygonal in section, and this sleeve is carried and is revoluble upon the exterior surface of the inner extension 15 16 of the casing 4, which receives within itself the end of the helical spring 13 and which also forms a bearing for the inner end of the spindle 1.

Fixed or formed upon the sleeve 15, which 20 carries the movable portion of the switch 14, is a ratchet-wheel 17, having ratchet-teeth formed upon that surface which faces the end of the motor-screw 10. This ratchet-wheel 17 is to receive a step-by-step rotative motion in one direction only each time that the operating-arm is rocked in either direction—that is, when the operating-arm 2 is rocked from its normal position in one direction the ratchet-wheel 17 will be passed 25 through one step of its motion—say counterclockwise—and similarly when the operating-arm 2 is rocked in the other direction the ratchet-wheel 17 will receive another motion, also in the same direction, (counter-clockwise.) The operating mechanism to effect 30 this result, which is provided to coact between the motor-screw 10 and the ratchet-wheel 17, consists as follows: The pawl-carrying ring 18, Figs. 1, 4, 9, and 10, is supported about its periphery by bearings in the casing. Such bearings conveniently consist 35 in the construction illustrated of two series of balls running in grooves formed one on each face of the ring 18 and having ball-races formed in collars which are fixed in the casing 3, and one of such collars 19 is made adjustable. The internal diameter of the ring 18 (see Figs. 9 and 10) is such as to freely receive the motor-screw 10, and the interior 40 periphery of the ring is formed with partial screw-threads 20, Fig. 9, which engage the grooves of the screw-threads upon the periphery of the motor-screw 10. By these means when the motor-screw is advanced in 45 the operative direction, as has been previously explained, the pawl-carrying ring 18 will be revolved between its ball-bearings through a definite angle, and when the motor-screw is withdrawn by the action of the spring 13 50 from the pawl-carrying ring the latter will be revolved in the opposite direction through a definite angle.

The ring 18 carries a number of plunger-pawls 21, (three in the construction now described,) and these pawls are clearly shown at Figs. 9 and 10, being cylindrical in formation and located in bores formed in the ring

18, so as to have motion parallel with the axis of the ring. Springs 22 act to impel the plunger-pawls laterally against the face-teeth 70 of the intermittent wheel 17, and the said pawls are formed with flat acting surfaces to engage the teeth when the ring 18 receives its motion in a driving direction.

It will be obvious that the construction of 75 the pawls carried by the pawl-ring may be varied, and a modified construction is shown at Figs. 13 to 16. In this construction the carrying-ring 23 takes the place of the pawl-ring 18 of Fig. 1 and is similarly supported 80 by the ball-bearings and actuated by the motor-screw passing through its central bore, as previously described. Instead, however, of the ring carrying plunger-pawls 21 the ring 23 of Figs. 13 and 14 is provided with seg- 85 mental projections 24 and bore-holes 25. Applied to the face of the ring 23 is a ratchet-ring 26, Fig. 15, having peripheral projections 27, which take in between the projections 24 of the ring 23, while the ratchet-teeth of the 90 ring 26 are held up against the teeth of the switch ratchet-wheel 17 by the springs acting in the bores 25 of the ring 23, as shown at Fig. 16. Thus when the ratchet-carrying ring 23 is revolved in a driving direction 95 the teeth of the ring 26 engage the teeth of the ratchet-wheel 17 of the switch and the latter is turned, while when the ring 23 is inoperatively returned to its position the ratchet-ring 26 passes inoperatively over the 100 teeth of the ratchet-wheel 17 by the resilient motion which can take place between the ring 26 and the ring 23.

Referring now to Figs. 1 to 4, the distance of motion of the parts is so regulated by the 105 length of the slot 12, within which the projections 11 of the motor-screw 10 can slide, that when the spindle 1 is revolved from its position of rest through its definite angle in one direction the pawl-carrying ring 18 will be 110 revolved in a driving direction through a definite angle, and its pawls 21, engaging the ratchet-teeth on the face of the intermittent wheel 17, will revolve the latter part through one step of its motion. Upon the spindle 1 115 being returned to its normal position of rest by the action of the spring 13 upon the ratchet-faced controlling-wheels the motor-screw 10 will be withdrawn from within the pawl-carrying ring 18, and the latter ring will be returned 120 with a rotary motion through the same angle which it originally advanced, and the parts will again be in the normal position shown on the drawings. A precisely similar coaction of the parts will take place when the spindle 125 receives an angular movement in an opposite direction, and the pawl-carrying ring 18 will again move through its definite angular movement in a driving direction and, again, by the action of the spring 13 upon the motor-screw 10, be returned to its normal position 130 ready for the next action, and so on.

In order to insure the ratchet-wheel 17, and consequently the moving switch part, against

backward motion, ratchet-teeth 28 are formed upon the periphery of the wheel 17, as shown at Fig. 11, and these teeth 28 are engaged by a spring-actuated detent-pawl 29, carried in a stationary bearing 30, Fig. 3, secured to the casing. To also insure the movable switch part against being carried by impetus beyond its required angle of motion, end projections 31 (three in number in the example shown) are formed on the end of the motor-screw 10, as is clearly shown at Figs. 1 and 7, and opposite projections 32 are also formed (six in number in the example shown) upon the face of the ratchet-wheel 17, and at or toward the termination of the advance motion of the motor-screw 10 the projections 31 come in between the projections 32 on the ratchet-wheel 17 and interlock, effectually preventing the switch part having further motion by impetus or otherwise.

What I claim as my invention, and desire to secure by Letters Patent, is—

1. In a rotary electric switch in which the moving part receives uniform step-by-step movements always in the same direction at every angular motion in either operative direction given to a spindle from a normal position of rest; the combination with the spindle, bearings to support the spindle, a motor-cylinder loose on the spindle, screw-threads on the periphery of the cylinder, means for preventing rotation of the motor-screw and for limiting the extent of its traverse movement along the spindle, means for advancing the motor-screw along the spindle by each operative angular movement of the spindle in either direction from a normal rest position, and means for limiting the angular motions of the spindle from and automatically returning it to its rest position; of a revolute annular ring carried in bearings in the framework, threads on the inner periphery of the ring to engage the threads of the motor-screw to cause the partial rotation of the ring 45 in one direction at the advance of the motor-screw and in the other direction at the return of the motor-screw, an electric switch having a revolute member, a stationary bearing to carry the revolute member, a face-toothed ratchet-wheel on the revolute switch member, engagement devices carried by the ring to engage the face-toothed ratchet-wheel in the operative direction of motion of the ring and to pass inoperatively over the teeth on the return movement of the ring, and means for preventing backward motion of the revolute switch part, substantially as set forth.

2. In a rotary electric switch in which the moving part receives uniform step-by-step movements always in the same direction at every angular motion in either operative direction given to a spindle from a normal position of rest; the combination with the spindle, bearings to support the spindle, a wheel fixed on the spindle and having inclined ratchet-like teeth on one face, an intermediate wheel loose on the spindle and having in-

clined face-teeth to engage with the teeth of the spindle-wheel, oppositely-inclined teeth on the other face of the intermediate wheel, a motor-cylinder loose on the spindle, screw-threads on the periphery of the cylinder, face-teeth on the end of the motor-screw to engage the adjacent teeth of the intermediate wheel, means for preventing rotation of the motor-cylinder and for limiting the extent of its traverse movements along the spindle and thereby also limiting the extent of angular motion of the spindle in either direction from a normal rest position, and a spring tending to hold the toothed wheels and motor-screw in engagement with one another and to thereby return the motor-screw and the spindle to rest after each operation; of a revolute annular ring carried in bearings in the framework, threads on the inner periphery of the ring to engage the threads of the motor-screw to cause the partial rotation of the ring in one direction at the advance of the motor-screw and in the other direction at the return of the motor-screw, an electric switch having a revolute member, a stationary bearing to carry the revolute member, a face-toothed ratchet-wheel on the revolute switch member, engagement devices carried by the ring to engage the face-toothed ratchet-wheel in the operative direction of motion of the ring and to pass inoperatively over the teeth on the return movement of the ring, and means for preventing backward motion of the revolute switch part, substantially as set forth.

3. In a rotary electric switch in which the moving part receives uniform step-by-step movements always in the same direction at every angular motion in either operative direction given to a spindle from a normal position of rest; the combination with the spindle, bearings to support the spindle, a wheel fixed on the spindle and having inclined ratchet-like teeth on the face, an intermediate wheel loose on the spindle and having inclined face-teeth to engage with the teeth of the spindle-wheel, oppositely-inclined teeth on the other face of the intermediate wheel, a motor-cylinder loose on the spindle, screw-threads on the periphery of the cylinder, face-teeth on the end of the motor-screw to engage the adjacent teeth of the intermediate wheel, means for preventing rotation of the motor-cylinder and for limiting the extent of its traverse movements along the spindle and thereby also limiting the extent of angular motion of the spindle in either direction from a normal rest position, and a spring tending to hold the toothed wheels and motor-screw in engagement with one another and to thereby return the motor-screw and the spindle to rest after each operation; of a revolute annular ring carried in bearings in the framework, threads on the inner periphery of the ring to engage the threads of the motor-screw to cause the partial rotation of the ring in one direction at the advance of the motor-screw and in the other direction at the return of the motor-screw, an electric switch having a revolute member, a stationary bearing to carry the revolute member, a face-toothed ratchet-wheel on the revolute switch member, engagement devices carried by the ring to engage the face-toothed ratchet-wheel in the operative direction of motion of the ring and to pass inoperatively over the teeth on the return movement of the ring, and means for preventing backward motion of the revolute switch part, substantially as set forth.

of the motor-screw, an electric switch having a revoluble member, a stationary bearing to carry the revoluble member, a face-toothed ratchet-wheel on the revoluble switch member, engagement devices carried by the ring to engage the face-toothed ratchet-wheel in the operative direction of motion of the ring and to pass inoperatively over the teeth on the return movement of the ring, and means for preventing backward motion of the revoluble switch part, and means to prevent the face-toothed ratchet-wheel and the rotary switch part being carried by impetus beyond its required angle of motion, substantially as set forth.

4. In a rotary electric switch in which the moving part receives uniform step-by-step movements always in the same direction at every angular motion in either operative direction given to a spindle from a normal position of rest; the combination with the spindle, bearings to support the spindle, an operating-lever fixed on the latter for partly rotating the spindle in either direction from a normal position of rest, a wheel fixed on the spindle and having inclined ratchet-like teeth upon one face, an intermediate wheel loose on the spindle and having inclined face-teeth to engage with the teeth of the spindle-wheel, oppositely-inclined teeth on the other face of the intermediate wheel, a motor screw-threaded cylinder loose on the spindle and having end face-teeth to engage the adjacent teeth of the intermediate wheel, means for preventing the rotation of the motor-screw, and for limiting its lateral motion in order to define the angular movements of the spindle in either direction from a normal position of rest, a spring tending to hold the toothed wheels and motor-screw in engagement with each other and to thereby return the motor-screw and the spindle to rest after each operation; of a revoluble annular ring carried in bearings in the framework, threads on the inner periphery of the ring to engage the threads of the motor-screw to cause the partial rotation of the ring in one direction at the advance of the motor-screw, an electric switch having a revoluble member, a stationary bearing to carry the revoluble member, a face-toothed ratchet-wheel on the revoluble switch member, engagement devices carried by the ring to engage the face-toothed ratchet-wheel in the operative direction of motion of the ring and to pass inoperatively over the teeth on the return movement of the ring, and means for preventing backward motion of the revoluble switch part, substantially as set forth.

5. In a rotary electric switch in which the moving part receives uniform step-by-step movements always in the same direction at every angular motion in either operative direction given to a spindle from a normal position of rest; the combination with the spindle, bearings to support the spindle, an operating-lever fixed on the spindle, a face ratchet-toothed wheel fixed on the spindle, an intermediate toothed wheel loose on the spindle to engage the spindle-wheel, a motor screw-threaded cylinder loose on the spindle having end teeth to engage the intermediate wheel, projections on the motor-screw, slots in the framework to receive the projections, and a spring to return the motor-screw and spindle to position; of an annular ring surrounding the motor-screw, bearings in the framework for the ring, projections from the ring to engage the screw, an electric switch having a revoluble member, a face-toothed ratchet-wheel on the revoluble member, spring-pawls carried by the ring to engage the face-teeth of the ratchet-wheel, ratchet-teeth on the periphery of the ratchet-wheel, and a spring detent-pawl carried by the framework.

6. In a rotary electric switch in which the moving part receives uniform step-by-step movements always in the same direction at every angular motion in either operative direction given to a spindle from a normal position of rest; the combination with the spindle, bearings to support the spindle, a wheel fixed on the spindle and having inclined ratchet-like teeth on one face, an intermediate wheel loose on the spindle and having inclined face-teeth to engage with the teeth of the spindle-wheel, oppositely-inclined teeth on the other face of the intermediate wheel, a motor-cylinder loose on the spindle, screw-threads on the periphery of the cylinder, face-teeth on the end of the motor-screw to engage the adjacent teeth of the intermediate wheel, projections on the motor-screw, slots in the framework to receive the projections, and a spring to return the motor-screw and the spindle to rest after each operation; of a revoluble annular ring carried in bearings in the framework, threads on the inner periphery of the ring to engage the threads of the motor-screw to cause the partial rotation of the ring in one direction at the advance of the motor-screw, an electric switch having a revoluble member, a stationary bearing to carry the revoluble member, a face-toothed ratchet-wheel on the revoluble switch member, engagement devices carried by the ring to engage the face-toothed ratchet-wheel in the operative direction of motion of the ring and to pass inoperatively over the teeth on the return movement of the ring, and means for preventing backward motion of the revoluble switch part, substantially as set forth.

7. In a rotary electric switch in which the moving part receives uniform step-by-step movements always in the same direction at every angular motion in either operative direction given to a spindle from a normal position of rest; the combination with the spindle, bearings to support the spindle, an operating-lever fixed on the spindle, a face ratchet-toothed wheel fixed on the spindle, an intermediate toothed wheel loose on the spindle to engage the spindle-wheel, a motor screw-threaded cylinder loose on the spindle having end teeth to engage the intermediate wheel, projections on the motor-screw, slots in the framework to receive the projections, and a spring to return the motor-screw and spindle to position; of an annular ring surrounding the motor-screw, bearings in the framework for the ring, projections from the ring to engage the screw, an electric switch having a revoluble member, a face-toothed ratchet-wheel on the revoluble member, spring-pawls carried by the ring to engage the face-teeth of the ratchet-wheel, ratchet-teeth on the periphery of the ratchet-wheel, and a spring detent-pawl carried by the framework.

to engage the peripheral ratchet-teeth to prevent backward motion, substantially as set forth.

7. In a rotary electric switch in which the 5 moving part receives uniform step-by-step movements, always in the same direction at every angular motion in either operative direction given to a spindle from a normal position of rest; the combination with the spindle, bearings for the spindle, an operative lever fixed on the spindle, a face-ratchet-toothed wheel fixed on the spindle, an intermediate toothed wheel loose on the spindle to engage the spindle-wheel, a motor screw-threaded cylinder loose on the spindle having end teeth to engage the intermediate wheel, projections on the motor-screw, slots in the framework to receive the projections, and a spring to return the motor-screw and spindle 10 to position; of an annular ring surrounding the motor-screw, bearings in the framework

for the ring, projections from the ring to engage the screw, an electric switch having a revolute member, a face-toothed ratchet-wheel on the revolute member, spring-pawl 25 carried by the ring to engage the face-teeth of the ratchet-wheel, ratchet-teeth on the periphery of the ratchet-wheel, and a spring detent-pawl carried by the framework to engage the peripheral ratchet-teeth to prevent 30 backward motion, projecting parts 31 on the forward end of the motor-screw, and projections 32 on the face of the ratchet-wheel 17 of the revolute switch part for preventing the latter being carried by impetus beyond 35 its required angle of motion, substantially as set forth.

WILLIAM KINGSLAND.
